UNITED STATES PATENT OFFICE.

JOHN T. QUIGLEY, OF FRESNO, CALIFORNIA, ASSIGNOR TO COSTMETER COMPANY, OF BOSTON, MASSACHUSETTS, A CORPORATION OF MASSACHUSETTS.

FILING AND INDEXING EQUIPMENT.

Application filed November 2, 1918, Serial No. 260,846. Renewed February 13, 1924.

To all whom it may concern:

Be it known that I, JOHN T. QUIGLEY, a citizen of the United States, and a resident of Fresno, in the county of Fresno and 5 State of California, have invented an Improvement in Filing and Indexing Equipment, of which the following description, in connection with the accompanying drawings, is a specification, like characters on 10 the drawings representing like parts.

This invention relates to filing and indexing equipments of the loose-leaf visible index class, in which the successive sheets overlap one another and present their identification-bearing margins to view substantially in one plane. The invention is more particularly concerned with means for locking sheet holders in their mounting, provision being made to prevent the unauthorized removal of any sheet. 20

My invention will be best understood by reference to the following description, when taken in connection with the accompanying drawings of one illustrative embodiment 25 thereof, while its scope will be more particularly pointed out in the appended claims.

In the drawings:

Fig. 1 is a front elevation of an indexing and filing equipment embodying my invention; 30

Fig. 2 is a sectional view on line 2—2 of Fig. 1, illustrating a sheet-holder and sheet-holder locking means in their normal positions;

Fig. 3 is a sectional view, similar to Fig. 2, showing the sheet-holder locking means unlocked, and one end of the sheet-holder brought forward preparatory to withdrawing the same from its place;

Fig. 4 is a vertical sectional view on an enlarged scale illustrating the sheet-holder locking means;

Fig. 5 is a sectional view on an enlarged scale on line 5—5 of Fig. 1;

Fig. 6 is a sectional view on an enlarged scale on line 6—6 of Fig. 1;

Fig. 7 is a view on an enlarged scale on line 7—7 of Fig. 1; and

Fig. 8 is a sectional view on an enlarged scale on line 8—8 of Fig. 1.

Referring to the drawings, and to the embodiment of my invention which is illustrated therein, I have shown for purposes of exemplification a filing and indexing equipment comprising a plurality of sheets

7 having overlapping identification-bearing margins 8, and having their opposite edges held by suitable sheet-holders 9, which may be and are in the present example in the form of cylindrical tubes slotted to receive 60 the sheets, which are suitably interlocked therewith. The sheet-holders may be supported in a mounting of any suitable character. In the present example, I have shown a mounting comprising a thin sheet metal 65 plate 10, having inwardly turned marginal flanges 11 and 12, forming channels 13 and 14, respectively, to receive the terminal portions of the sheet-holders 9. The latter hold the margins of their respective sheets in 70 properly spaced relationship, and since their terminal portions are cylindrical, they constitute trunnions about whose axes the sheets may be turned to present either face to view, while still preserving the proper spacing 75 of the trunnions.

The sheets may be either upstanding or depending, as circumstances may require, the latter arrangement being herein shown for purposes of exemplification. Upward movement of the sheet-holders in their channels may be limited by any suitable means, such as a pair of stops 15 and 16, herein in the form of blocks presenting obstructions disposed in respective channels 13 and 14, and held in place therein by rivets 17 and 18, extending through the blocks and through the back of the plate 10. Similarly, downward movement of the sheet-holders in their respective channels may be limited by stops 80 19 and 20, held in place by rivets 21 and 22, as clearly shown in Fig. 1. The sheet-holders are confined between the upper and lower stops, and rest upon one another in a continuous series. If desired, the upper 85 and lower ends of the plate 10 may be bent to form inwardly directed flanges 23 and 24.

As best shown in Fig. 2, the flanges 11 and 12 normally overlie the ends of the sheet-holders 9. It is desirable that the sheet-holders shall be normally locked in place, so that accidental or unauthorized removal shall be impossible, while on the other hand, it is equally desirable that any given sheet and sheet-holder may be removed instantly 100 when it is necessary. I have, therefore, provided means for normally locking the sheet-holders against endwise movement, but adapted to unlock the sheet-holders to permit the latter to be moved endwise, thereby to 105 110

withdraw their ends from beneath one of the flanges. To this end, I have herein provided a locking bar 25, having suitable provision so that in one position, as shown in Fig. 2, the sheet-holders are locked against undue lengthwise movement, while when the bar is moved into another position, such as that shown in Fig. 3, the given sheet-holder may be shifted lengthwise, thereby to release one end from beneath the flange 11, as illustrated in Fig. 3, and the other end then withdrawn from beneath the flange 12, as illustrated in Fig. 3. To this end, the locking bar is mounted to turn about an axis extending lengthwise of the channel 14, the major portion of the cross section of the bar being at one side of the axis, as by making the bar semi-cylindrical. When, therefore, the bar is in the position shown in Fig. 2, it prevents escape of the sheet-holder, while on the other hand, when the bar is turned 90 degrees into the position shown in Fig. 3, the sheet-holder may be moved lengthwise to release one end from beneath the flange 11, whereupon the other end may be withdrawn from beneath the flange 12.

The locking bar may be mounted in any suitable bearings, but it is convenient to employ for this purpose the upper and lower stops 16 and 20, as clearly shown in Fig. 4. Preferably, the bar is provided with upper and lower reduced portions 26 and 27, mounted to turn in the upper and lower bearings, and providing shoulders 28 and 29 to hold the bar against axial movement. Preferably, the bar is held in its normal position by suitable means, which will yield and allow the bar to be turned to its unlocked position, and when released will restore the bar automatically to its normal position. To this end, I have herein provided a spring 30, preferably helically coiled about the reduced portion 27 of the bar, said spring having its upper end secured to the block 20, as at 31, and its lower end secured to an enlarged portion 32 of the bar, as at 33. It should be understood that the spring is constantly under tension in the proper direction, so that it always tends to maintain the bar in the locking position shown in Fig. 2. Turning movement of the bar under the influence of the spring may be limited by any suitable means, such as a stop 34, shown in Fig. 7, herein consisting of a pin mounted in the block 20 and permitting the rod to turn through an arc of only 90 degrees.

In order to prevent accidental or unauthorized removal of the sheets, I have herein provided the locking means with a key 35, which may be of any appropriate character, but in the present example, comprises a cylindrical rod mounted to turn in the bearing 36, and suitably interengaging with the locking bar, whereby the latter

may be turned by turning the key. To this end, I have herein provided the locking bar with a tongue 37, and the key 35 with a slot 38 to receive the same. By inserting the key in its bearing 36, it may be interlocked with the locking bar, and the latter operated in the above-described manner. On the other hand, when the key is removed, it is impossible for an unauthorized person to turn the locking bar. If desired, suitable means may be provided normally to hold the key in its place, and to this end, I have herein provided the shank of the key with a circumferential groove 39, best shown in Fig. 5, to receive an appropriate detent which may be, and is herein, a spring 40 formed of a piece of wire suitably secured to the plate 10 as by rivets 41 and 42. Preferably, the groove 39 is of such depth and shape that the key may be removed when desired by simply exerting sufficient force to cause the spring to ride out of the groove, without the necessity of lifting the spring by the use of the other hand. Preferably, also, the inner end of the key is suitably beveled as at 43, so that when it is introduced, the spring will be lifted automatically, and caused to ride along the surface of the key shank until the groove 39 registers with the spring 40, when the latter will snap into place, and hold the key until it is intentionally removed.

Having thus described one specific embodiment of my invention, what I claim and desire by Letters Patent to secure is:

1. An equipment of the class described comprising in combination, a plurality of sheets, a plurality of sheet-holders, a sheet-holder mounting, sheet-holder locking means including a pivoted locking-bar, and a key cooperating with said locking-bar.

2. An equipment of the class described comprising in combination, a plurality of sheets, a plurality of sheet-holders, a sheet-holder mounting, sheet-holder locking means including a pivoted locking-bar, and a key interengaging endwise with said locking-bar and providing a handle for turning the latter.

3. An equipment of the class described comprising in combination, a plurality of sheets, a plurality of sheet-holders, a sheet-holder mounting, sheet-holder locking means including a pivoted locking-bar, a key cooperating with said locking-bar, and a yielding detent to hold said key in cooperating relationship with said locking-bar.

4. An equipment of the class described comprising in combination, a plurality of sheets, a plurality of sheet-holders, a sheet-holder mounting, sheet-holder locking means including a pivoted locking-bar, a key cooperating with said locking-bar, and a yielding detent to hold said key in cooperating relationship with said locking-bar, said key

and detent having cooperating means providing for operation of said detent into and out of holding relationship with said key by the mere insertion and withdrawal of the 5 latter.

5. An equipment of the class described comprising in combination, a plurality of sheets, a plurality of sheet-holders, a sheet-holder mounting, sheet-holder locking means 10 including a pivoted locking-bar, a key cooperating with said locking-bar, and a yielding detent to hold said key in cooperating relationship with said locking-bar, said key having a beveled end and a lateral detent 15 receiving depression adapted to displace said detent laterally upon axial movement of said key.

6. An equipment of the class described comprising in combination, a support provided with a pair of flanges extending towards each other and forming opposed sheet-holder receiving channels, a plurality of sheet-holders greater in length than the space between said flanges, and having their 25 opposite ends normally covered by said flanges, and sheet-holder locking and unlocking means normally locking said sheet-holders against endwise movement and adapted to unlock said sheet-holders to permit the latter to be moved endwise thereby to withdraw their ends from beneath one of said flanges, said locking and unlocking means including a locking-bar extending lengthwise of and adjacent the other flange 30 35 and pivoted to swing toward and from said sheet-holders, and a key cooperating with said locking-bar.

7. An equipment of the class described comprising in combination, a support provided with a pair of flanges extending towards each other and forming opposed sheet-holder receiving channels, a plurality of sheet-holders greater in length than the space between said flanges, and having their 40 45 opposite ends normally covered by said flanges, and sheet-holder locking and unlocking means normally locking said sheet-holders against endwise movement and adapted to unlock said sheet-holders to permit the latter to be moved endwise thereby to withdraw their ends from beneath one of said flanges, said locking and unlocking means including a locking-bar extending lengthwise of and adjacent the other flange and 50 55 pivoted to swing toward and from said sheet-holders, and a key interengaging endwise

with said locking-bar and providing a handle to turn the latter.

8. An equipment of the class described comprising in combination, a series of sheets, a series of sheet-holders, a sheet-holder mounting in which said sheet-holders are mounted for movement from a normal locked position to an unlocked position in which they are removable from said mounting, sheet-holder locking means including an actuating bar adapted to move said sheet-holders from an unlocked position to a locked position, and a handle removably attached to said bar, which handle when attached 70 to said bar is adapted to move the latter from one of such positions to the other.

9. An equipment of the class described comprising, in combination, a series of sheets, a series of sheet-holders, a sheet-holder mounting in which said sheet-holders are mounted for movement from a normal locked position to an unlocked position in which they are removable from said mounting, sheet-holder locking means including 80 an actuating bar adapted to move said sheet-holders from an unlocked position to a locked position, a handle removably attached to said bar, which handle, when attached to said bar is adapted to move the latter from 85 one of such positions to the other, and retaining means to retain said handle in its position of attachment to said bar.

10. An equipment of the class described comprising in combination, a series of sheets, a series of sheet-holders, a sheet-holder mounting in which said sheet-holders are mounted for movement from a normal locked position to an unlocked position in which they are removable from said mounting, sheet-holder locking means including 90 an actuating bar adapted to move said sheet-holders from an unlocked position to a locked position, a handle removably attached to said bar, which handle, when attached to 95 said bar is adapted to move the latter from one of such positions to the other, and retaining means to retain said handle in its position of attachment to said bar, said handle and retaining means having provision 100 for effecting the retention of said handle by the mere movement of the latter from one position to another.

In testimony whereof, I have signed my name to this specification.

JOHN T. QUIGLEY.
